VACUUM CLEANER SWITCH

Gustaf Einar Lofgren, Rye, N. Y., assignor to
Electrolux Corporation, Dover, Del., a corpora-
tion of Delaware

Application November 22, 1933, Serial No. 699,097

14 Claims. (Cl. 200—52)

My invention relates to vacuum cleaners and more particularly to actuating apparatus for switch mechanism therefor.

The principal object of my invention is to provide a switch actuating means which can be easily operated by the foot.

The nature and advantages of my invention will be clear from the following description taken in conjunction with the accompanying drawings forming a part of this specification and of which:

Fig. 1 is a vertical sectional longitudinal view of a vacuum cleaner unit embodying the invention;

Fig. 2 is an end view of the apparatus shown in Fig. 1 with certain of the parts removed;

Fig. 3 is a top view of switch actuating mechanism embodying the invention;

Fig. 4 is a vertical sectional view taken on the line 4—4 of Fig. 3;

Fig. 5 is a sectional view taken on the line 5—5 of Fig. 3;

Fig. 6 is a sectional view taken on the line 6—6 of Fig. 4;

Fig. 7 is a sectional view taken on the line 7—7 of Fig. 4;

Fig. 8 is a side view of part of the switch actuating mechanism;

Fig. 9 is a top view of another form of the invention;

Fig. 10 is a sectional view taken on the line 10—10 of Fig. 9;

Fig. 11 is a sectional view taken on the line 11—11 of Fig. 10;

Fig. 12 is a sectional view taken on the line 12—12 of Fig. 9;

Fig. 13 is a sectional view taken on the line 13—13 of Fig. 10;

Fig. 14 is a top view of another form of the invention;

Fig. 15 is a sectional view taken on the line 15—15 of Fig. 14;

Fig. 16 is a sectional view taken on the line 16—16 of Fig. 15;

Fig. 17 is a sectional view taken on the line 17—17 of Fig. 15;

Fig. 18 is a perspective view of a detail; and

Fig. 19 is a sectional view taken on the line 19—19 of Fig. 15;

Referring to Figs. 1 and 2, a vacuum cleaner unit 10 is mounted on a carpet or surface 11 by means of runners 12 fastened to end rings 9 and 13 at the ends of a barrel 15. The barrel is preferably cylindrical. On the top of the cylinder are mounted a forward handle bracket 16 and a rear handle bracket or housing 17. The

handle 18 has an end pin 19 slidably mounted in the forward bracket 16 and an end pin 20 retained in the rear bracket 17. The end members 21 and 22 are secured to the forward and rear rings 9 and 13 respectively by any suitable means such as spring clips 23.

Within the casing of the vacuum cleaner unit is a motor 24 resiliently mounted on a ring 14 made of electrically non-conducting material attached to ring 9. The motor is connected to 10 drive a fan 25 for causing flow of air into the inlet opening 26 through a dust bag 27 and out through the outlet opening 28. The motor 24 is supplied with electricity by means of leads 29 which are connected to a switch mechanism 30. 15 The switch mechanism is shown more in detail in Fig. 7 and includes contact pieces 31 and 32 adapted to be contacted by a contact roller 33 mounted on a slotted bar 34 and adapted to travel on a track 35. The bar 34 engages and is moved by a pivoted switch arm 36 pivoted at 37 to a frame 38 secured as by screws 39 and 40 to the ring 14. A spring surrounding member 34 presses against member 36. A rounded head 41 on the upper end of lever 36 sets in a recess 42 in a switch bar 43 which is manually movable horizontally and transversely in recesses 44 in the rear handle bracket 17. Screw 39 is provided with an upper projection 45 which enters a recess 46 in the switch member and constitutes a stop for limiting the sideways movement of the switch member. The switch member may be moved by hand to make or break electrical contact. In the position shown in Fig. 7 contact is made and the motor is in operation. If the bar 43 is moved to the left (as shown in Fig. 7) the head 41 is moved to the left whereby the lower end of lever 36 is moved to the right and this causes snap action movement of the roller 33 to the left away from the contact pieces 31 and 32, thus 20 breaking the electrical connection.

The switch bar 43 has a notch 48 on the upper side thereof into which fits a pivoted shaft member 49, so-called because it has an end 50 which may be round or of other shape, on which is loosely journalled a roller 51. The shaft member or lever 49 passes through the recess 46 and is pivoted about a stud-bolt 52 which passes through the end cap 17 and is screwed into ring 9. The shaft member 49 extends loosely through a horizontal recess 54 in the cover member or bracket 17 and the roller 51 is outside the cover. It will be noted that the parts are all loosely put together and no fine machine work is required. The roller is substantially in the form of a hemisphere 25 30 35 40 45 50 55

and rests in a channel 66 formed by a plate 57 which has a flange 58 held under the cover plate. Member 57 is rounded and provides a bearing surface for the roller 51. The stud-bolt 52 serves to hold all of the parts 20, 17, 48, 49, 51 and 57 in position.

The purpose of the roller 51 is to provide a switch actuating mechanism which can be easily operated by the foot. The cleaner unit of the kind shown in Fig. 1 rests on the floor and may stand approximately eight inches high. The operator has a suction hose in the hand which is connected to the inlet 26. The roller 51 obviates the necessity of bending over to push the switch bar 48. The foot can be placed on the roller and rolled whereupon arm or shaft member 49 will be swung and will engage one side or the other of the groove 48 to move the switch bar and cut the motor in or out. The arrangement is such that pressure on the roller 51 causes no friction between member 49 and the adjacent parts. The roller extends above the bracket or housing 17. The housing may be provided with a raised rim 59 to prevent the foot from scratching the top surface of the casing 17 which may be polished or nickel-plated. A fine scratch on the raised rim 59 would not detract from the appearance. The roller 51 is knurled to obtain good contact with the foot. The stop 45 limits lateral movement of the shaft member 49. By mounting the roller loosely on the shaft member the foot may continue to rotate the roller although the member 49 has come to the limiting position. The device is sturdy and can withstand abuse and yet is easy to operate.

Fig. 9 shows another embodiment of the invention in which the shaft member 62 corresponding to the part 49 of the previous embodiment is pivoted intermediate its ends on the stud-bolt 52. The roller 51 is loosely mounted on the end of arm 62 and rides in a channel 66 formed in a casting 61 which also holds the pin 20 of the handle 18. A ridge 60 is formed in the casting for the purpose previously described. With this arrangement the roller moves in the opposite direction from the hand switch bar 48 as clearly appears in Fig. 11. By placing the roller 51 between the switch hand bar 48 and handle 18, a removable contact plug 63 may be inserted in an opening 64 so as to unify the electrical connections. The plug is inserted onto contact points 65. Thus a unitary housing is provided for holding the end of the handle, for containing the contact points for the electrical cord plug, and for supporting the foot and hand switches.

In the arrangements shown in Figs. 14 through 18, the roller 51 moves parallel to the hand switch bar 48. Hand bar 48 is notched on the top at 67 and a shaft member 68 formed as shown in Fig. 18 fits into the notch 67 leaving a journal 69 extending outwardly. The roller is loosely mounted on the part 68. The roller extends above bracket housing 17 and rests in the U-shaped plate member 70 which is formed with shoulders 71 providing bearing surface for the roller 51. The roller has a centrally knurled portion and laterally reduced portions which rest on the shoulders 71. The shaft member 68 has downwardly projecting parts 72 which fit between the member 70 and hand bar 48. This affords easy assembly inasmuch as the member 68 can be placed on the hand bar and inserted in the recess 74 in which the part 68 moves and this sub-assembly is held in place by the bracket or housing 17, all of the parts being then held together by the screws 75.

Switch cover or housing 17 may be provided with ridges 76 adjacent the roller 51 and additional ridges 77 so as not to mar the surface of the switch cover. The movement of the parts may be limited by the same arrangement as shown in Fig. 7 or edges of the slots 74 may constitute the limiting means.

It will be seen that in all the embodiments the switch may be operated either by hand or by means of the foot-operated roller. In all of the embodiments the roller is loosely mounted on the journal or shaft member and can turn even though the switch mechanism proper has reached its limiting position.

What I claim is:

1. An electric switch actuating mechanism for a vacuum cleaner comprising means providing a channel open at the top, a roller in said channel bearing on the bottom thereof and projecting above said channel to be rolled by foot, a switch arm, and means for moving said switch arm upon movement of said roller.

2. An electric switch actuating mechanism for a vacuum cleaner comprising a switch housing, a switch arm projecting into said housing, a bar engageable with said arm, so as to transmit motion thereto, a shaft member movable with said bar, a roller loosely mounted on said shaft member, and a member providing a channel and bearing surface for said roller.

3. An electric switch actuating mechanism for a vacuum cleaner comprising means providing a channel open at the top, a roller in said channel bearing on the bottom thereof and projecting above said channel to be rolled by foot, a shaft member on which said roller is loosely mounted, and a switch arm operable by lateral movement of said shaft member.

4. An electric switch actuating mechanism for a vacuum cleaner comprising means providing a channel open at the top, a roller in said channel bearing on the bottom thereof and projecting above said channel to be rolled by foot, a shaft member on which said roller is loosely mounted, a hand switch bar on which said shaft member is mounted, and a switch arm operable by movement of said roller and said bar.

5. An electric switch actuating mechanism for a vacuum cleaner comprising a switch arm, a pivoted lever connected to said switch arm so as to transmit motion thereto, a roller loosely mounted on the end of said lever, and a supporting surface for said roller.

6. An electric switch actuating mechanism for a vacuum cleaner comprising a roller loosely mounted on a movable arm, a hand bar interconnected to move with said arm, a switch arm movable thereby, and a supporting surface for said roller.

7. A vacuum cleaner unit comprising a horizontally mounted casing, a switch mounted within said casing having a switch arm projecting through the top thereof, a channel member secured to the top of said casing, a roller mounted to roll in and be supported by said channel member and being movable by foot contact, and means for transmitting motion from said roller to said switch arm.

8. A vacuum cleaner unit having a housing member, an electric switch, a foot operated roller projecting above said housing member for actuating said switch, means for supporting said roller directly beneath the place of application of the foot, and a ridge on said housing member adjacent said roller.

9. A vacuum cleaner unit comprising a switch, a housing, a grooved member held in said housing, a roller in said grooved member projecting above said housing to be contacted by the foot, and means whereby movement of the roller actuates the switch, said grooved member supporting said roller directly beneath the place of contact with the foot.

10. An electric switch actuating mechanism for a vacuum cleaner including a switch housing, a pivotally mounted switch arm projecting into said housing, a slidably mounted bar formed with a recess therein, one end of said switch arm extending into said recess so that longitudinal movement of said bar causes pivotal movement of said arm, a shaft member movable with said bar, a roller rotatably mounted on said shaft member, and a member providing a channel and bearing surface for said roller.

11. A foot operated switch assembly particularly adapted for use with an electric motor driven vacuum cleaner having a housing for the motor and coacting parts, comprising: a switch casing rigidly connected to the housing, a spring-pressed toggle switch operatively connected into the motor circuit and including a pivotally mounted switch arm, a swingably mounted operating lever for said switch having an outwardly projecting head arranged to be actuated by the foot of an operator, said lever having a loose operating connection with said switch arm whereby when the toggle is actuated past dead

center it will throw with a snap action irrespective of the speed of travel of said lever, said casting being constructed to limit travel of said lever and to act as an abutment to protect the lever against excessive foot pressure.

5

12. An electric switch actuating mechanism for a vacuum cleaner including a switch arm movable to open and close a switch, a pivotally mounted foot-operated member connected to said arm so as to transmit motion thereto, and means for supporting said member in all positions directly beneath the point of application of the foot.

13. An electric switch actuating mechanism for a vacuum cleaner including a switch arm movable in a plane to open and close a switch, a member movable in a plane substantially at right angles to the first mentioned plane and connected to said arm so as to transmit motion thereto, a roller adapted to be contacted by the operator's foot loosely mounted on said member, and means forming a track for supporting said roller.

14. An electric switch actuating mechanism for a vacuum cleaner including a switch arm movable to open and close a switch, a pivotally mounted member connected to said arm so as to transmit motion thereto, a roller loosely mounted on said arm and adapted to be contacted by the operator's foot, and an arcuate track for supporting said roller.

GUSTAF EINAR LOFGREN.
